UNITED STATES PATENT OFFICE.

HENRY I. HARRIMAN, OF HYDE PARK, MASSACHUSETTS.

WEFT-REPLENISHING LOOM.

No. 870,509.

Specification of Letters Patent.

Patented Nov. 5, 1907.

Application filed September 11 1905. Serial No. 277,818.

To all whom it may concern:

Be it known that I, HENRY I. HARRIMAN, a citizen of the United States, residing at Hyde Park, in the county of Norfolk, State of Massachusetts, have invented a certain new and useful Improvement in Looms, of which the following is a specification, reference being had therein to the accompanying drawings.

Broadly stated, the invention consists in the combination in a loom, with means for effecting a predetermined corrective result, and a weft or filling-indicator operating in case of the happening of a predetermined contingency in connection with the working weft-supply to call or indicate for the functional operation of the said means for the attainment of such result, of a secondary weft or filling-indicator or detector which controls the consummation of the said result.

The invention is shown herein applied in a loom employing instrumentalities for replenishing automatically the working weft-supply therein with an interruption in the regular weaving action corresponding with merely the interval represented by a certain number of picks in the weaving, the said loom being of the class in which the replenishing instrumentalities are called into action prior to the complete exhaustion of the weft-supply that is carried by the shuttle on the lay, when the said weft-supply has become depleted to a predetermined extent. In this instance the corrective result consists in restoring the loom to its normal weaving action with replenished working weft-supply. In a loom of the class in question a measuring or gaging device, which may be termed generally a feeler, is employed to act in connection with the wound mass of weft or filling that is contained within the working shuttle on the lay, to detect when the said mass has been depleted to the predetermined extent by the delivery of the weft or filling from the shuttle in the course of the weaving. The said feeler is in operative control of the replenishing instrumentalities, and is intended to call or indicate for the functional operation of the said instrumentalities in advance of the complete exhaustion of the weft-supply that is carried by the working shuttle, so as thereby to lessen the opportunities for the occurrence, in the cloth which is being woven, of the defect in the weaving which results if the shuttle leaves within a shed in the warps a length of weft-thread extending only part way across the width of the cloth and constituting an incomplete or partial pick. The theory is that the feeler or equivalent device shall indicate or call for the replenishing operation while there still remains within the shuttle on the lay a quantity of yarn sufficient to insure the introduction of a full or complete pick of weft by the shuttle, in the last flight of the shuttle from the feeler end of the loom to the feeding end thereof preliminary to the accomplishment of such operation. It being practically impossible to ascertain with close precision by means of the feeler or equivalent device the

exact length of weft remaining within the shuttle, it usually occurs in practice that in order to be on the safe side the feeler is set or adjusted so as to cause it to call or indicate for the replenishing operation while there remains a fairly considerable quantity of weft or filling within the shuttle. This quantity, which is greater or less according to circumstances and the closeness to accuracy with which the feeler or equivalent device is set, becomes waste in consequence of being discarded from the loom. Manufacturers prefer to incur loss in this respect, in order to avoid the greater loss which would result from the lowering of the cloth in grade by the existence of defects therein due to partial or incomplete picks or lengths of weft.

One general object of the invention is, in the case of a loom in which weft-replenishment is effected automatically, to enable the margin of waste to be reduced by rendering it safe and feasible to set the feeler or its equivalent to measure with greater closeness with respect to the end of the supply of weft or filling within the shuttle.

A second general object of the invention is to guard against defects in the weaving of the character that would occur if, after the feeler has called or indicated for the corrective action of the replenishing instrumentalities, the pick of weft that is laid in the shed of the warps by the shuttle in its flight from the feeler-end of the loom to the feeding-end thereof should not extend entirely across the width of the cloth.

These general objects are attained in conformity with the present invention, in the case of a loom such as referred to, through the employment of a secondary weft-indicator or detector which acts to ascertain whether or not the weft or filling extends entirely across the cloth after the flight of the shuttle from the feeler-end of the loom to the feeding-end thereof, and which controls the consummation of the predetermined corrective result, in such case the automatic replenishment of the depleted working weft-supply and resumption of the weaving action.

In the drawings,—Figure 1 is a view, mainly in side elevation, but partly sectional, showing certain portions of the weft-replenishing instrumentalities of a loom in which my invention is adapted to be embodied. Fig. 2 is a plan view showing certain parts of Fig. 1. Fig. 3, Sheet 2, is a detailed view in side elevation showing certain portions of a feeler-mechanism, the working shuttle being in vertical transverse section. Fig. 4, Sheet 2, shows in front elevation the parts of Fig. 3. Fig. 5, Sheet 2, shows the parts of Figs. 3 and 4 in plan. Fig. 6, Sheet 3, shows in vertical transverse section part of a loom having applied thereto a secondary weft-indicator or detector in conformity with my invention. Fig. 7, Sheet 4, shows in plan the features of Fig. 6. Fig. 8, Sheet 5, shows the secondary weft-indicator or detector and associated parts

- in the positions which are assumed thereby when the weft or filling is present, as when a complete or full length pick is laid through the shed in the warps, at the time of the operation of the said indicator or detector. Fig. 9, Sheet 5, is a view similar to Fig. 8, showing the parts in the positions which are assumed thereby at the time of the operation of the secondary indicator or detector when the weft or filling does not extend in position to be acted upon by the said device.
- 10 Having reference to the drawings, — the opposite side-frames or end-frames of a loom are designated 1, 1, 2 being the breast-beam.
- 3 is the crank-shaft, and 4, Figs. 1 and 6, is the cam-shaft.
- 15 5, Figs. 6 to 9, is a pitman or connecting-rod connecting one of the cranks with the lay, 6 being the lay-sword, 611 the lay-rockshaft, and 7 the lay-beam.
- 8 is the shipper rockshaft which is mounted in bearings with which the side-frames of the loom are provided, and extends across the loom beneath the breast-beam, 9 being a shipper-handle which is made fast upon one end of the said rockshaft.
- 20 In Fig. 1, 10 is a portion of the picking-stick at the feeding end of the lay, and in Fig. 2, 11 is the slot that is formed through the lay-beam, extending lengthwise of the latter, within which the said picking-stick plays back and forth.
- 25 Figs. 1 and 2 show certain parts of weft-replenishing instrumentalities which may be employed in carrying my invention into effect. In the said figures, 12 is a hopper for fresh or reserve shuttles, the said hopper being supported in place adjacent one end of the breast-beam. 121 is a shuttle-support, which is pivotally mounted at 122 in connection with the hopper, 30 and furnished with rearwardly-projecting fingers that normally occupy a position beneath the bottom shuttle in the hopper, supporting such shuttle and the others which rest upon the latter. 13 is the injector, its supporting lever being mounted pivotally at 14 upon the lower part of the loom-frame. The short arm of the said lever is provided with a roll 15, which latter is held pressed in contact with the periphery of an edge-cam 16 that is carried by the change-shaft 17, by the tension of a contracting spiral spring 18 having 35 one end thereof engaged with the injector-lever and the other end thereof engaged with the eye of a bolt 19, applied to a bracket 20 which is attached to the loom-frame. Normally the change-shaft, together with the cams which are fast thereon, stands motionless in the 40 position represented in Fig. 1, and the injector occupies the position beneath the hopper which it occupies in such figure. When the change-shaft is caused to rotate, a preliminary forward movement of the injector occasioned by cam 16 carries the injector against a 45 downwardly-extending finger 123 of the shuttle-support, moving the latter forward so as to withdraw its rearwardly-extending fingers from beneath the bottom shuttle in the hopper and permit the contents of the hopper to drop until the bottom shuttle rests upon the horizontal shuttle-supporting portions 131 of the 50 injector. The spring 18 next operates to move the injector with yielding force rearward toward the lay, under the control of the cam 16, to place the shuttle which is held thereby within the shuttle-box, after 55 which the said cam acts to communicate positive movement to the injector in the opposite direction, namely forward toward the breast-beam, and thereby restores the injector to its normal position shown in Fig. 1. At 22, Figs. 1 and 2, is the front-plate of the shuttle-box at the feeding-end of the loom, it being 60 movable to enable the same to be withdrawn from its normal position at the front of such shuttle-box, to open the box to permit the spent working shuttle on the lay to be discharged from the shuttle-box and a fresh or reserve shuttle to be inserted into the latter 65 through the action of the injector. The front-plate 22 is carried by forwardly-projecting arms 231, 231, forming part of a rocker 23, the rockshaft of which last is pivotally mounted in bearings that are provided in brackets 24, 24, which are attached to the lay-beam 70 and rise at the rear thereof. Normally the front-plate 22 is held depressed in its working position, so as to keep the shuttle-box closed, by means of a contracting spiral spring 25, Fig. 1, having one end thereof connected to one of the forwardly-projecting arms 231 75 of the rocker and the other end thereof connected to one of the brackets 24. For the purpose of operating the rocker to raise the front-plate to open the shuttle-box to permit of the discharge of the spent working shuttle and the introduction of a fresh or reserve shuttle, the rocker is provided with a rearwardly-projecting arm 232 having connected therewith one end of a connecting-rod 26, the opposite end of which is connected to an arm 27, which is pivotally mounted at 28 and provided with a projection that is engaged by the 80 periphery of an edge-cam 29 which is fast upon the change-shaft. In the rotation of the change-shaft, the cam 29 transmits movement through the arm 27 and connecting-rod 28 to the rocker to raise the front-plate 85 from its normal closed position and thereby open the 90 shuttle-box. The spring 25 acts to move the rocker in the reverse direction under the control of the cam 29, to lower the front-plate to its normal position and thereby close the shuttle-box again. An ejector 30 is mounted by means of brackets 31, 31, upon the back 32 of the shuttle-box, the said ejector being formed as a rocker having journals which are fitted to bearings in the said brackets, and having fingers 301, 301, which project into 95 openings at the rear of the shuttle-box as indicated in Figs. 1 and 2. The ejector is held retracted normally 100 by the tension of the contracting spiral spring 33, the latter having one extremity thereof engaged with a screw or the like projection carried by the rock-shaft of the rocker 23, while the other end of the said spring is connected with a strap 341 that wraps part way 105 around the rock-shaft of the ejector and is attached by its inner end to the said rock-shaft. A finger 302 projecting rearward from the ejector takes against the under side of the rock-shaft of the rocker 23, and serves to limit the extent of the retraction of the ejector under 110 the action of the spring 33. A finger 303 projecting forwardly from the ejector is pressed against by one of the arms 231 of the rocker 23 in the movement of the rocker by which the front-plate 22 of the shuttle-box is raised, and thereby the ejector is actuated to eject 115 the spent working shuttle from the opened shuttle-box. The ejected shuttle falls from the said shuttle-box upon a flexible apron 34, the latter being connected at its upper end with the front of the lay-beam and passing 120 forward from the lay-beam over a transverse rod 35 125 130 135

which is supported at the rear of the shuttle-receiving box 36, the latter being attached to the adjacent side-frame of the loom. The shuttle slides from the apron 34 into the said box 36. The apron plays back and forth over the rod 35 as the lay vibrates, and thereby accommodates itself to the varying positions of the lay, it serving to conduct the ejected shuttle into the box 36 whatever may be the position of the lay at the time of the ejection. In the looms of this 10 type the lay and other weaving instrumentalities are caused to stand still for the performance of the replenishing operation, and are restarted after the fresh shuttle has been placed in the shuttle-box at the feeding end of the lay, after which the change-shaft comes to 15 rest. Certain of the devices for automatically restarting the weaving instrumentalities are shown in Fig. 1, and comprise the cam 37 on the change-shaft 17, the lever 38 pivoted at 28 and having a projecting portion which is held pressed against the periphery of the said 20 cam by the action of the contracting spiral spring 39, a rod 40 which is provided with an adjustable collar 41 to be engaged by the said lever 38, an arm 42 which is mounted to swing loosely upon one end of the shipper rock-shaft 8, an arm 43 which is fixedly mounted 25 upon the said rock-shaft, and a strong spring 44 connecting the said arms. As the change-shaft 17 nears the end of its rotation the cam 37 moves the lever 38 against the tension of spring 39, causing the said lever to engage with the collar 41 and move the rod 40 end- 30 wise toward the rear of the loom, this movement of the rod swinging the arm 42 and the latter transmitting through the spring 44 movement to the arm 43 and rock-shaft 8 to turn the said rock-shaft so as to cause the weaving instrumentalities to be shipped into action 35 again as in the application aforesaid. The spring 44 is of sufficient strength to transmit movement to the shipper rock-shaft when the latter is not prevented by a positive force from turning. When, however, the rock-shaft 8 is prevented by a positive force from turning, the said spring yields or stretches as hereinafter explained. This provision for yielding forms a feature of the present invention.

A convenient arrangement of feeler mechanism is shown in Figs. 3, 4 and 5 of Sheet 2, in which figures 45 45 is a movable swell that is mounted upon a pivot carried by the lay, at the front of the shuttle-box at the end of the loom opposite that at which the feeding or shuttle-changing takes place. The said swell has a short arm 451 having connected therewith one end of a contracting spiral spring 46, the other end of which is engaged with a bracket 47 projecting forward from the lay-beam. The said spring acts with a tendency to move the free extremity of the swell rearwardly into the said shuttle-box. As the working shuttle enters the latter at the 50 end of its flight across the loom from the feeding-end it presses the said swell forward. The swell co-acts with a spring piece 48 which is applied to the shuttle-body and occupies a slot in the front wall of the latter adjacent the base of the bobbin or cop which is contained within the shuttle. The swell has a forward projection or detent 461 for co-operation with a detent-plate 49 that is mounted upon the upper end of a vertical bar or slide 50, the latter being supported in a guide 51 at the front of the lay-beam 7, and having in 55 the operation of the loom a vertical reciprocation com-

municated thereto. For the purpose of producing this reciprocation the said bar or slide 50 has connected with its lower end a rod 52 having its lower end pivotally joined to a bolt 53 which is mounted in a guide 54 upon the loom-frame, the said bolt having combined therewith a spring 55 acting with a tendency to hold the same in its lowest position relative to the said guide 54. The point of pivotal connection between the rod and the bolt is eccentrically located with reference to the axis of the lay rock-shaft, and consequently the 60 rod and the lay vibrate about different centers as the lay swings back and forth. The difference between the path described by the lay-beam and that described by the upper end of the rod occasions a vertical movement of the bar or slide through its guide upon the front of the lay-beam, the parts being so arranged that as the lay goes rearward the bar or slide rises, and as the lay goes forward again the bar or slide descends. Each time the shuttle enters the shuttle-box at the feeler-end of the lay, it passes into a position in which the slot 80 and spring-piece are presented to the swell, and by the action of the swell against the said spring-piece, the latter is pressed inward toward the base of the bobbin or cop. The extent of the rearward movement of the swell under the action of its spring is determined by the size of the wound mass of weft or filling at the said base. So long as the quantity of weft or filling in the shuttle is sufficient for continued weaving, the swell is pressed forward so that its projection or detent 461 is kept beneath the detent-plate 49 of the vertical bar 85 or slide 50, and engages therewith in the descent of the said bar or slide which is occasioned by the forward swing of the lay, so as to prevent the bar or slide from making a full downward movement. When the bar or slide is arrested in its descent, the spring 55 yields to permit the bolt 53 to rise sufficiently to accommodate the further movement of the lay toward front center. The vertical bar or slide 50 is provided with a forwardly projecting knock-piece or bunter 56 which is designed to coact with a projection of a depending arm 58 which is fixed upon one end of a horizontal rock-shaft 59 that is journaled in fixed bearings 60, 60, at one end of the breast-beam. At its inner extremity, the said rock-shaft 59 has an upwardly extending arm 63 that is provided with a pin 64 which extends beneath a dog or pawl 65 that is connected pivotally at its front end to an arm 66 rising from the rod or shaft 67, the latter being mounted in a bearing 68 at the under side of the breast-beam, and having the arm 69 serving for the transmission of movement to the parts by which the change-shaft is caused to rotate, and also having a projecting piece 69 which acts against a projection 91 of the shipper-handle 9 to turn the latter in order to arrest the action of the weaving instrumentalities for the purposes of the replenishment. The parts by 100 which the rotation of the change-shaft is effected may be constructed and arranged to operate as in my application aforesaid. By means of a torsional spring 105 70 surrounding a portion of the horizontal rock-shaft 59 and having one extremity thereof engaged with one of the bearings 60 for the said rock-shaft, and the other extremity thereof engaged with a collar 61 that is fast upon the said rock-shaft, the rock-shaft is held normally in a position in which the stop 581 which is provided on the depending arm 58 thereof is caused to en- 110 115 120 125 130

gage with the stand 601, and in which the pin 64 of the upwardly extending arm 63 supports the rear end of the dog or pawl 65 above the path of the striker-arm 71, the latter being vibrated by means of a cam 72, 5 Fig. 4, upon the cam-shaft 4 of the loom. When the detent-plate 49 catches upon the top of the projection or detent 461 of the swell 45, the vertical bar or slide 50 is arrested in its descent before the knock-off piece or bunter 56 has been lowered into position to engage 10 with the projection 57 of the depending arm 58 of the horizontal rock-shaft 59 as the lay moves forward. Consequently the lay completes its advance without engagement of the said knock-off piece or bunter with the said projection. The horizontal rock-shaft is not 15 turned, and the pin 64 on its upwardly projecting arm 63 continues to hold the dog or pawl 56 out of position for being engaged by the striker-arm 71. As soon, however, as the delivery of the weft or filling from the shuttle has decreased the size of the final or base portion 20 of the wound mass within the shuttle to the predetermined extent, the rearward movement of the swell 46 which then is permitted carries its projection or detent 461 clear of the path of the detent-plate 49, allowing the vertical bar or slide 50 to complete its 25 descent. By this completion of the said descent, the knock-off piece or bunter 56 carried by the said vertical bar or slide is caused to assume a position opposite the projection 57 of the depending arm 58 of the horizontal rock-shaft 59, and as the lay continues its forward move- 30 ment the engagement of the said knock-off piece or bunter with the said projection causes the rock shaft to be turned, moving the pin 64 of the upwardly projecting arm 63 rearward beneath the recess 561 of the dog or pawl 56 and lowering the free end of the said 35 dog or pawl into the path of the engaging end of the striker-arm 71. The striker-arm now engages with the dog or pawl, pushing the same forward so as to turn the cross-rod and thereby start the change-shaft into motion as well as arrest the working of the weaving in- 40 strumentalities.

The secondary weft-indicator or detector which in the illustrated embodiment of the invention controls the consummation of the predetermined corrective result is shown in Figs. 6 to 9. In such figures, *a* is a fork 45 or feeler that is mounted upon the pivot *b* at the rear of the lay-beam, at the upper surface of the latter and adjacent the shuttle-box at the feeding end of the loom. The said fork or feeler is furnished with an arm *c* projecting at an angle with respect to the portion of the said 50 fork or feeler which makes contact with the weft or filling. A torsional coil spring *d*, Fig. 7, applied to the pivot *b*, and having one extremity thereof engaged with the fork and the other with the pivot, acts with a tendency to swing the fork forward and downward to feel for 55 weft or filling between the selvage of the cloth that is being woven and the adjacent shuttle-box after the entrance of the shuttle into the said shuttle-box at the conclusion of its flight across the loom from the feeler-end of the latter. The upper part of the lay-beam is 60 recessed at *e*, as indicated by the dotted lines in Figs. 6, 8 and 9, in order that the fork may descend into the recess in its forward movement in case there is no weft or filling in its path. A grid *f* is applied over the recess to support the weft or filling against the pressure of the 65 tines of the fork. The fork *a* has combined therewith

means for raising and retracting the same, and in practice it normally is held in the position in which it is shown in Fig. 6 out of the path of the working shuttle. To these ends, in the present instance the fork is provided with an arm *a'*, and a rod *g* mounted to slide in the direction of its length through a guide *g'* on the lay is provided with an arm or cam-piece *h* for engagement with the arm *a'* of the fork. Lengthwise movement of the rod *g* in an upward direction carries the upper end of the said arm or cam-piece *h*, which is rounded off at the rear side thereof to render its action upon the arm *a'* of the fork gradual and easy, against the under side of the said arm *a'*, and by the action of the arm or cam-piece *h* against the arm *a'* the fork is turned upward and rearward to the position of Fig. 6. The arm *h* normally 75 remains in contact with the arm *a'* in the position of Fig. 6 and during the regular working of the loom holds the fork *a* in its uplifted retracted position. Downward movement of the rod *g* and arm *h* releases the fork to the action of its spring *d*, which thereupon turns the fork 80 forward and downward to feel for the weft or filling. If when this movement of the fork occurs the weft or filling extends from the selvage of the cloth to the shuttle in the adjacent shuttle-box, it supports the fork *a* in the position shown in Fig. 8. In case no weft or filling extends from the selvage to the said shuttle, the fork *a* descends to the position in which it is shown in Fig. 9. The rod *g* is operatively combined with the weft-replenishing mechanism, and when the operation of the said 85 mechanism is called or indicated the said rod is operated to occasion the action of the fork or feeler *a*. The lower end of the rod passes through a hole in the free extremity of an operating lever *i* which is mounted upon a pivotal support *i'* carried by a bracket or stand *i''* that is attached to the side-frame at the feeding-end 90 of the loom. The said lever is held in engagement with the periphery of a cam *j* upon the change-shaft 17 by means of a contracting spiral spring *k* having one end thereof engaged with the lever and the other end thereof engaged with a stand *k'* that is attached to the adjacent side-frame. 95

A collar *g'* is fixed upon the rod *g* above the lever *i*, and the lower portion of the rod is encircled by an expanding coil-spring *g''* which is compressed between the lever and a collar *g''* that is fixed upon the rod. While 100 the change-shaft occupies its position of rest the low portion or hub of cam *j* is presented to lever *i*, which latter occupies its elevated position, and in consequence of the engagement of the said lever with the upper collar *g'* the lever holds the rod *g* in its upper position, thereby causing the fork *a* to be kept in its up-raised and retracted position during the ordinary working of the loom. When the change-shaft is caused to rotate for the purpose of occasioning the feeding operations, the cam *j* operates in the concluding portion of 105 such rotation to depress the lever *i*, and the latter, acting against the spring *g''*, transmits through the said spring the required force for moving rod *g* and its arm or cam-piece *h* downward so as to release the fork or feeler *a* to the action of spring *d* and permit the same to be moved by the latter spring to feel for weft or filling. In order that the subsequent operations may be controlled by the fork or feeler *a*, the arm *c* of the same is notched as shown in Figs. 6, 8, and 9, and the upper end 110 of rod *g* is provided with a projection or engaging por- 115

tion g^5 to engage in the notch. The arm a and projection g^5 are so related that in case the fork or feeler a is supported by weft or filling as in Fig. 8 the said arm will occupy a position in which its notch will remain in the 5 path of the descending projection g^5 , so that the said projection will enter the said notch, as in Fig. 8. There- by the rod g will be arrested in its downward move- ment, and the further downward movement of the lever i under the action of the cam j on the change-shaft will 10 only compress the spring g^3 . Should the weft or filling be absent so as to permit the fork or feeler a to assume the position of Fig. 9, the arm c will be swung forward with relation to the path of projection g^5 , and rod g will be permitted to accompany lever i to the full extent of 15 the movement that is communicated thereto by the cam j . To the rod g is secured a block m having pivoted thereto the lower end of a rod n which passes upward, at the rear of the breast-beam through a fixed guide n' . Upon the upper end of rod n is fixed a pro- 20 jection n^2 . To a bracket o attached to the breast-beam is pivoted a detent p having a lug p' and handle p^2 . Normally, the detent is held swung rearward as shown in Figs. 6 and 8 into a position in which it is clear of the arm p^4 of the shipper rockshaft 8, by means of the tor- 25 sional spring p^3 , Fig. 7. The lug p is designed to be en- gaged by the projection n^2 in case rod n is caused to de- scend to the full extent that is indicated in Fig. 9, and in such case the contact of the projection with the lug in the descent of the rod turns the detent forward into po- 30 sition to engage with the arm p^4 of the shipper rockshaft as in Fig. 9. In Fig. 8 the shipper rockshaft is free to be turned by the action of the restarting devices after the shuttle has been changed, to cause the loom to continue the weaving operation with the fresh shuttle which has 35 been placed upon the lay. In Fig. 9, however, the shipper-rod is prevented from being turned by the said devices, and consequently the weaving operation is not resumed. When arm p^4 is engaged by the detent p so as to prevent the shipper rockshaft from being returned 40 by the action of the restarting devices, the spring 44 connecting arm 42 with arm 43 of the said rockshaft yields, permitting arm 42 to move while arm 43 is held from moving. The handle p^2 of detent p enables such detent to be operated manually, as in case it is desired by the workman to disengage the said detent from the 45 arm p^4 of the shipper rockshaft.

The invention is not necessarily limited to use in connection with weft-replenishing instrumentalities of the precise type and character shown and described herein, nor in looms in which the weft-replenishment is effected 50 by changing the working shuttle. Nor is it restricted with respect to the precise character of the weft or filling indicators or detectors, or to the manner in which the secondary indicator or detector controls the consummation of the predetermined corrective result. 55

I claim as my invention:—

1. In a loom, in combination, means for effecting a predetermined corrective result, a weft- or filling indicator indicating for the functional operation of the said means for the attainment of such result in case of predetermined condition of the working weft-supply, and a secondary weft-indicator or detector which controls the consummation of the said result. 60
2. In a loom, the combination with instrumentalities for replenishing the working weft-supply, and a detector indicating the said instrumentalities into action in case of depletion of the said weft-supply to a predetermined extent, of a secondary weft-detector operating in the absence of weft or filling on the return of the shuttle to the feeding end of the loom to prevent the consummation of 70 the replenishing action. 65
3. In a loom, the combination with weft-replenishing instrumentalities, and a weft- or filling-indicator calling or indicating for the operation of the said instrumentalities on depletion of the working weft-supply to a predetermined extent, of a weft- or filling-detector operating to call or indicate for stoppage of the loom on absence of weft or filling from the shed on the return of the working shuttle to the feeding end of the loom. 75
4. In a loom, the combination with weft-replenishing instrumentalities, and a weft- or filling-detector adapted to ascertain absence of weft or filling from the shed on the return of the working shuttle to the feeding end of the loom, and operating to call or indicate for stoppage of the loom in case of such absence, of a weft- or filling-indicator calling or indicating the said instrumentalities and weft- or filling-detector into action on depletion of the working weft-supply to the predetermined extent. 80

In testimony whereof I affix my signature in presence of two witnesses.

HENRY I. HARRIMAN.
